PRODUCTION OF USEFUL MATERIALS

Jacquelin E. Harvey, Jr., Washington, D. C., assignor of one-half to Southern Wood Preserving Company, East Point, Ga., a corporation of Georgia

Application October 9, 1942, Serial No. 461,500

4 Claims. (Cl. 196—49)

The instant invention relates to the production of toxic oils employable as fungicides, insecticides, and for any other service to which toxic oils may be put.

More especially the instant invention relates to the production of toxic oils from mixtures of petroleum fractions characterized by ring structure content. Among such starting materials may be mentioned mixtures of petroleum fractions characterized by ring structure content recovered from petroleum fractions by well known extraction methods including extractive distillation and azeotropic distillation. Also may be mentioned mixtures of petroleum fractions characterized by ring structure content as flowing from thermal and/or catalytic treatment of certain petroleum fractions which includes petroleum fractions having ring structures induced in the course of thermal and/or catalytic treatment, as for example having ring structures induced in the course of one or more thermal and/or catalytic treatments of unusual length, as for example, for periods of 1-10 hours or more.

An object of the instant invention is the production of toxic oils from the aforesaid petroleum fractions or others whereby to provide oils of the preservative type, as for example preservative wood impregnants conforming to specifications extant or acceptable to the trade consuming such oil materials.

Another object of the instant invention is the provision of preservative wood impregnants having evaporation rates under given conditions acceptable to the trade.

Another object of the instant invention is the reforming of the above named mixtures of hydrocarbons or others whereby to induce toxicity.

Still another object of the instant invention is the induction of usable toxicity in the presence of a gas or gaseous mixtures.

Yet another object of the instant invention is the induction of toxicity in the above named mixtures of petroleum fractions or others, the while or afterwards providing specific means which guard against diminution in said toxicity.

Another object of the instant invention is the release of latent toxicity in the above named mixtures of petroleum fractions or others.

Another object of the instant invention is the release of latent toxicity in the above named mixtures of petroleum fractions or others by increasing the water solubility of said materials.

Other objects of the instant invention will be apparent as flowing from the following disclosures and examples.

In the past wood preservative oils of the high temperature coal tar derived type have been employed in quantities greatly exceeding the total of all other wood preservative oils. From the standpoint of availability of said coal tar as the parent material of wood preservative oils, it is annually produced in this country under normal conditions to the extent of five hundred million to six hundred million gallons. This quantity of coal tar is capable of yielding an amount of highly effective wood preservative oils which would make this country self sufficient in its wood preservative requirements. However, due to the fact that when a wood preservative distillate (creosote) is recovered from coal tar there remains in the still a residue (pitch) which, at best, is a low priced product and which, at worst, is a seriously distress product to the end that at times it is placed in inventory rather than sold, the current method of processing coal tar leaves much to be desired. The net result of this situation obtaining is that the coal tar distiller usually confines himself to that distillation recovery of creosote which would correspond to the attending amount of pitch that he can market at a profit. Accordingly, over a period of years several hundred million gallons of creosote oil have been imported into this country. That such a situation should obtain is apparently a paradox in that we annually produce a quantity of high temperature coal tar which if processed to yield creosote would make us self sufficient in that requirement. A survey of this paradox is fully outlined in an address given by no less an authority than S. P. Miller, technical director, The Barrett Company, 40 Rector Street, New York city, before the Franklin Institute, Philadelphia, Pennsylvania, in December, 1932. The economics of coal tar have not materially changed since that date.

In view of the apparent inability of the coal tar industry to provide national needs of wood preservative oils, a strong incentive is given to groups processing other types of oil to invade the lucrative wood preservative market. At the present time many types of aromatic oils are produced by the petroleum industry, and the high boiling oils of aromatic content produced by this industry have for several years been tested for their wood preservative efficiency.

By the term "petroleum aromatic" as used herein and in the appended claims is meant to include mixtures of petroleum fractions characterized by cyclic content and includes specifically various forms and types of naphthenes found in

various mixtures of petroleum fractions, as for example monocyclic and polycyclic naphthalenes.

The so-called petroleum aromatics which includes the monocyclic and polycyclic naphthalenes and unsaturated hydrocarbon fractions have in the past been produced in very large quantities. However, very little work has been done on these materials. Such a fact is borne out on page 667 "Reactions of pure hydrocarbons" Gustav Egloff, Reinhold Publishing Corporation, 330 West 42nd Street, New York city, which states:

"Despite the fact that naphthalenes or cycloparaffines are available in enormous quantities, as shown by an estimate of 100,000,000 barrels present in the 1,498,000,000 barrels of crude oil which was the world's production in 1934, comparatively little work of a pyrolytic nature has been performed on individual naphthalene hydrocarbons or the cycloolefins."

Several oils of cyclic content produced by the petroleum industry have been inspected for their toxicity to wood destroying fungi, among which may be mentioned a high boiling oil of cyclic content produced (1940) at the Wood River refinery of the Shell Oil Company and which has the following inspection:

Gravity	10.8

¹ Maximum.

In the foregoing tabular data P. M. C. C. means Pensky-Martin Closed Cup; C. O. C. means Cleveland Open Cup.

Upon evaluating the foregoing oil for its toxicity to wood destroying fungi (Madison 517), it was found that this oil did not inhibit the growth of the fungi named at a concentration of up to and including 10%.

It is now discovered that the oil above named or other oils of cyclic content produced by the petroleum industry can be increased in toxicity in accordance with the process of the instant invention.

According to the instant invention oils of cyclic content produced by the petroleum industry are reformed, transformed, modified and/or converted to oils of a more toxic nature having characteristics acceptable to consumers of wood preservative impregnant and/or conforming to wood preservative specifications extant.

Consumers of wood preservative impregnant are at times loath to change from an old and tried preservative impregnant to a new and untried product unless the new product has physical and chemical characteristics which to a great degree indicate that the new product would have

good life service after its impregnation into the material to be preserved.

The following examples will illustrate several modes of practicing the process of the present invention. The single figure of the drawing represents a flow sheet of the process.

The instant invention is based on, among other things, the discovery that if an oil of cyclic content produced by the petroleum industry having relatively little toxicity and more than 30% saturates in the materials boiling between 270° C. and 355° C., as for example an oil of cyclic content produced by well known extraction methods is (1) subjected to a thermal and/or catalytic treatment at a relatively high pressure and thereafter (2) subjected to further thermal and/or catalytic treatment at a relatively low pressure whereby to provide a newly formed oil having less than 30% but more than 5%, and preferably more than 10% saturates in the materials boiling between 270° C. and 355° C., the finally converted material is adapted to yield an oil of the wood preservative type characterized by induced toxic properties, substantial residual matter above 315° C. or 355° C. and a specific gravity falling between the limits of 0.85 and 1.10, preferably between 0.95 and 1.05.

Example 1.—A mixture of petroleum fractions characterized by cyclic content selected from the group consisting of aromatic extracts, extractive distillates, azeotropic distillates and fractions having induced cyclic structures as flowing from thermal and/or catalytic action, repeated or otherwise, as for example an aromatic extract of a mixture of high boiling petroleum fractions, said extract boiling entirely above 240° C., characterized by more than 30% saturates in the materials boiling between 270° C. and 355° C. and relatively little toxicity is reformed, modified and/or converted by the present process and toxicity induced therein.

According to the process of the present invention the feed stock is reformed, modified and/or converted in the liquid phase at a temperature selected between the limits of 400-600° C., as for example at a temperature of 450° C. whilst under a pressure of 1,000 pounds for a period of 30 minutes. The partially beneficiated material is passed to a second treating zone where without substantial reduction in temperature it is maintained at a pressure of 500 pounds for a period of 30 minutes.

The beneficiated material is cooled and inspected, and found to have less than 30% but more than 5% saturates in the 270-355° C. fraction and a substantial percentage of newly formed fractions boiling below 210° C. The oil is also characterized by pronounced induction of toxicity. The overall beneficiated material is stabilized to provide a residual as an oil of the wood preservative type having induced toxic properties, about 5% boiling at 210° C. and in excess of 5% boiling above 355° C.

Other things being equal, the toxicity of a preservative oil is proportional to its percentage of unsaturates, that is to say, as the percentage of unsaturates increases, the toxicity of the preservative becomes more pronounced. It is well understood in the art that the materials in a preservative impregnant boiling between 270° C. and 355° C. are among the least toxic. However, it is discovered that if an attempt is made to convert the entirety of the materials boiling between 270° C. and 355° C. into unsaturates, reactions take place that are prejudicial to the conversion of

the oil to toxic substances, as for example there occurs inordinate gasification and/or reformed high boiling materials that approach fixed carbon as an upper limit.

It is, therefore, an important part of the present process to so control and coordinate the reforming, modifying and/or converting action in both of the process steps as to provide a treated material having less than 30% but more than 5%, and preferably more than 10% saturates in the fraction boiling between 270° C. and 355° C. Such a control of saturates in the named fraction has the effect of making toxicity more pronounced while at the same time obviating the operating ills above mentioned.

Example 2.—A mixture of petroleum fractions boiling preponderantly above 210° C. having substantial residual matter above 355° C. characterized by cyclic structures and relatively little toxicity is charged to a pressure vessel and maintained at a temperature of 440° C. whilst under a pressure of 2,000 pounds for a period of 25 minutes. At the end of the named period the pressure is reduced to 1,000 pounds and the temperature elevated to 450° C. The material undergoing treatment is held under the last named conditions for a period of 20 minutes.

The beneficiated material is cooled and inspected and found to have in the 270°-355° C. fraction less than 25% but more than 5% saturation. Further inspection discloses that the material has induced toxicity. The overall beneficiated material is fractionally distilled to provide a distillate as an oil of the wood preservative type characterized by induced toxic properties boiling 1½% at 235° C. and with 15% boiling above 355° C.

The wood preservative impregnant of the present process which is recovered from the overall processed oil is not circumscribed by any single boiling limitation, but is rather circumscribed by published wood preservative specifications and/or the preference and acceptance of wood preservative consumers.

Accordingly, after the stated oils have been processed to provide materials of induced toxic properties in the manner stated herein, the preservative impregnant may be segregated from the benefited material to provide a residual, distillate or extract which conforms to any of the following published wood preservative specifications:

WOOD PRESERVING IMPREGNANTS

Specifications

1. American Wood Preservers' Association
  - a. Up to 210° C., not more than 5%
  - b. Up to 235° C., not more than 25%
2. American Wood Preservers' Association
  - a. Up to 210° C., not more than 1%
  - b. Up to 235° C., not more than 10%
  - c. Up to 355° C., not less than 65%
3. American Wood Preservers' Association
  - a. Up to 235° C., not more than 1½%
  - b. Up to 300° C., not more than 16½%
  - c. Up to 355° C., not less than 45%
4. American Wood Preservers' Association
  - a. Up to 210° C., not more than 8%
  - b. Up to 235° C., not more than 35%
5. American Wood Preservers' Association
  - a. Up to 210° C., not more than 10%
  - b. Up to 235° C., not more than 40%

6. American Wood Preservers' Association
    - a. Up to 210° C., not more than 5%
    - b. Up to 235° C., not more than 15%
  7. Prussian Ry.
    - a. Up to 150° C., not more than 3%
    - b. Up to 200° C., not more than 10%
    - c. Up to 235° C., not more than 25%
  8. National Paint Varnish and Lacquer Association #220
    - a. 5% at 162° C.
    - b. 97% at 270° C.
  9. Southern pine shingle stain oil
    - a. 5% at 137° C.
    - b. 95% at 257° C.
  10. Neville shingle stain oil
    - a. I. B. P., 150° C.
    - b. 5% at 205° C.
    - c. 95% at 292° C.
  11. Carbolineum 270° C., I. B. P.
- Example 3.*—A liquid sulfur dioxide extract of a mixture of high boiling petroleum fractions, said extract boiling preponderantly above 240° C. having substantial residual matter above 315° C. and relatively little toxicity is passed through a series of tubes set in a furnace and rapidly brought up to a temperature of 445° C. whilst under a pressure of 1800 pounds. The thus heated material is discharged to a vessel where it is held under a temperature of substantially 455° C. whilst in the presence of water gas at a pressure of 1200 pounds for a period of one hour. At the end of the hour period the treated material is cooled and inspected and found to have induced toxic properties. It is also found that a substantial percentage of fractions boiling below 210° C. has been induced and that the materials boiling between 270-355° C. have less than 25% but more than 5% saturates.
- The material of induced toxic properties is then stabilized to provide a residual as an oil of the wood preservative type characterized by induced toxic properties, boiling 1% below 210° C. and having in excess of 10% materials boiling above 315° C.
- Instead of employing water gas as the extraneous gas, hydrogen may be employed and the partial pressure of the gases may be 5-50% or more. Also employable as extraneous gases are methane and its homologues, various refinery gases, inert gases such as nitrogen and those containing carbon. Various purposes are accomplished by the employment of the gas of extraneous source, among which may be mentioned the thermal protection of the material undergoing reformation, conversion, transformation and/or modification in order to avoid excess carbonaceous deposits and/or conversion of fractional parts of the material to forms that are substantially non-toxic. If a gas reactive under the process conditions is employed, this gas may also assist in the accomplishing of the stated purpose or others. The employment of the extraneous gas or gases noted, separately or in admixture, are to be in one mode of operation, specifically read into all examples in either or both of the process steps. Particular benefits flow from the employment of the gas of extraneous source in both of the process steps, but the employment of the gas in only one step has a partial benefit toward toxicity induction, as for example by employing the gas of extraneous

source in the final step above noted which is characterized by a reduction in pressure.

Example 4.—A furfural extract of high boiling petroleum fractions, said extract boiling entirely above 250° C. having substantial residual matter above 355° C. and relatively little toxicity is passed through a series of tubes set in a furnace and rapidly brought up to a temperature of 470° C. whilst under a pressure of 2500 pounds. The thus seated material is discharged to an enlarged vessel and held at a temperature of substantially 450–460° C. whilst under a pressure of 1500 pounds for a period of one hour.

The overall beneficiated material is fractionally distilled to recover a distillate as an oil of the wood preservative type characterized by induced toxic properties boiling 90% between 210° C. and 355° C.

Inspection of the preservative distillate discloses that the 270–355° C. fraction has more than 5% but less than 30% saturates.

Example 5.—A flashed petroleum residuum boiling entirely above 270° C. and with substantial residual matter above 355° C. characterized by cyclic structures and relatively little toxicity is passed through a series of tubes set in a furnace and rapidly brought up to a temperature of 430° C. whilst under a pressure of 750 pounds. Thereafter, the heated material is discharged into an enlarged zone and maintained at a pressure of 300 pounds where without substantial reduction of temperature it is held for such a period as to provide more than 5% but less than 25% saturation in the 270–355° C. fraction.

The heat treated material is fractionally distilled to recover a distillate having substantially no ends boiling below 200° C. and with 75% boiling up to 315° C. Upon inspection of the distillate it is found to have toxic properties in excess of the parent feed stock.

Instead of recovering the oil of the instant process as a distillate or stabilized residual, the overall beneficiated oil may be extracted with a suitable solvent, as for example with phenol, furfural, liquid sulfur dioxide, cresol, xylol, cresylic acid, aniline, nitrobenzene, chloroaniline, nitrotoluene or the like. After the beneficiated material has been extracted the raffinate is then discarded. The solvent is removed from the extract and the preservative oil of the instant process recovered from the extract as a stabilized residual or a distillate. However, if the extract has a boiling range in accordance with published wood preservative specifications tabulated in the foregoing, the overall extract may be used as the oil of the instant process.

Example 6.—A petroleum oil of induced cyclic structures boiling preponderantly above 210° C., having in excess of 20% residual matter boiling above 355° C. and relatively little toxicity is brought up to a temperature of 450° C. whilst under a pressure of 3,000 pounds and held at that temperature for a period of 30 minutes. Thereafter, the heat treated material is discharged into an enlarged zone where without substantial reduction in temperature it is held at a pressure of 2,000 pounds for a period of 30 minutes.

The heat treated material is cooled and inspected and is found to have newly induced fractions boiling below 270° C. and more than 5% but less than 30% saturation in the 270–355° C. fraction. Upon further inspection the oil is found to have induced toxic properties; however, the materials boiling above 270° C. have a rel-

atively low toxicity as compared to materials boiling below that temperature. The beneficiated material is cut at a temperature of 270° C. and the high boiling materials heat treated at a temperature of 440° C. whilst under a pressure of 3,000 pounds for a period of 20 minutes. After the 20 minute period the material is discharged into an enlarged zone where it is held without a substantial reduction of temperature under a pressure of 2,000 pounds for a period of 20 minutes.

The thus heat treated residual is commingled with the once beneficiated fractions boiling below 270° C. whereby to provide an overall comminglement having a toxicity in excess of the overall once beneficiated oil. The commingled materials are fractionally distilled to recover a distillate as an oil of the wood preservative type characterized by induced toxic properties having about 3% distilling below 150° C., substantial residual matter boiling above 355° C. and less than 25% but more than 5% saturates in the materials boiling between 270° C. and 355° C.

Instead of retreating the entirety of the materials boiling above 270° C. only a portion thereof may be retreated and certain toxicity benefits will flow therefrom.

Instead of commingling the entirety of the retreated residual and the entirety of the temporarily discarded and once treated low boiling fractions, only a portion of these two materials may be commingled, provided that the commingled fractional parts provide the desired preservative oil or furnish an oil capable of yielding the desired preservative impregnant.

The temperatures employable in the process steps are selected between the limits of 350–600° C., and preferably between 400–500° C.

The pressures in the first step of the process are in excess of atmospheric and are preferably in excess of 20 atmospheres, say pressures selected between the limits of 50–200 atmospheres. However, pressures as high as practicable may be employed. In the second step of the process, pressures in excess of atmospheric are generally preferred. However, in the event it is elected to operate the first and relatively high pressure step at, say a pressure of from 5 to 50 atmospheres, the relatively low pressure in the second step may be at atmospheric pressure, or below if desired.

The time element of the instant process is so coordinated with the overall pressures in both steps, the relative reduction of pressure in the second step and the temperatures in both steps as to provide in the 270–355° C. fraction of the overall finally beneficiated material a saturation less than 30% but more than 5%. A few trials with any selected starting material will enable those skilled in the art to provide the correct coordination.

Various catalysts assist in the heat treating of the starting petroleum oils whereby to provide induced toxic properties. These catalysts are employable in either the vapor phase or the liquid phase, or both, and this provision may in one mode of operation be specifically read into either or both of the steps of all examples.

Among such catalysts may be mentioned the various metals, their oxides, sulfides and carbonates, cellulosic materials and carbon, activated or otherwise. Various silicious materials including the various clays shaped or prepared in appropriate form may also be employed.

Various synthetic gels, as for instance the well

known hydrogels may be employed as catalytic materials including specifically gelatinous precipitates properly prepared. Also employable are halogens, halids and derivatives thereof, including specifically substitution and addition products thereof, as for example and specifically substitution and addition products of said derivatives, say a hydrogen halid or the like.

These catalytic materials above mentioned are effective in promoting the provision of the oils of the wood preservative type having induced toxic properties and these catalytic materials separately, in admixture or two or more employed simultaneously, are to be in one mode of operation, specifically read into all examples in either or both of the process steps.

Carrying on the process in either or both of the steps in the presence of catalytic materials has the effect of smoothing out the operation, shortening the time necessary for toxicity induction and/or making operations permissible at lowered temperatures. The most effective catalysts are silicious materials, activated carbon, halogens and derivatives thereof, cellulosic materials, synthetic gels and the oxides, sulfides and carbonates of metals.

I claim:

1. In the production of a preservative wood impregnant from the mixture of petroleum fractions boiling preponderantly above 270° C. characterized by a substantial percentage of materials of cyclic structure content and inher-

ent but inhibited toxicity, the process which comprises: heat treating said petroleum fractions at a temperature selected between the limits of about 370-600° C. while under a relatively high pressure for a period not in excess of about 30 minutes; thereafter heat treating said material in entirety at a temperature selected between the limits above named at a relatively low pressure for a period not in excess of about one hour; inducing toxicity into the materials under treatment by coordinating the time of treatment in both periods of heating as to provide in the converted material less than about 30% but more than about 5% saturation in the 270-355° C. fraction; and segregating from the beneficiated material an oil of the wood preservative type boiling preponderantly between 210° C. and 355° C., having an end point at least as high as about 355° C. and substantial residual materials boiling above 315° C., and in the fraction 270-355° C. less than about 30% but more than about 5% saturates.

2. The process of claim 1 with inclusion of carrying on at least one of the operational steps in the presence of an extraneous gas.

3. The process of claim 1 with inclusion of carrying on the process in the presence of catalytic material.

4. The process of claim 1 in which the segregated wood preservative is a distillate.

JACQUELIN E. HARVEY, Jr.
